MUFFLER

Matthew G. Zinsitz, Brookfield, Wis.

Application September 20, 1938, Serial No. 230,852

3 Claims. (Cl. 181—57)

This invention relates to an improved muffler more particularly intended for use with internal combustion engines, and seeks, among other objects, to provide a device of this character which will be operative for greatly reducing back pressure in an exhaust pipe with the result that the efficiency and economy of operation of the engine is greatly improved.

Another object of the invention is to provide a muffler which is simple in construction and which may be manufactured cheaply.

Another object of the invention is to provide a muffler which will be effective for preventing blocking of the muffler inlet pipe with motor waste.

A further object of the invention is to provide a muffler which, in view of the fact that back pressure will be greatly reduced by the use thereof, will permit highly efficient emission of exhaust gases, quick starting of the engine, maximum fuel efficiency, and reduction of carbon in the engine cylinders and exhaust manifold structure.

Other objects of the invention will become apparent during the course of the following description.

The invention is illustrated in the accompanying drawing, wherein:

Figure 1 is a longitudinal sectional view of my improved muffler.

Figure 2 is a vertical sectional view on the line 2—2 of Figure 3.

Figure 3 is a vertical transverse sectional view on the line 3—3 of Figure 1.

Figure 4 is a vertical sectional view on the line 4—4 of Figure 1.

Referring now to the drawing, wherein, as will be seen, similar numerals of reference are employed to designate like parts throughout the various views, the numeral 1 indicates in general, the body of my improved muffler. The body is formed preferably from a pair of mating sections 2 and 3 which are pressed from single sheets of suitable metal and have their inner circumferential edges welded, as shown at 4, to define a unitary muffler body. As best seen in Figure 3 of the drawing, the body 1 is formed with a circular wall 5 and substantially flat end walls 6 and 7.

In order to attach my improved muffler to an internal combustion engine exhaust pipe, such as shown at 8, I provide an inlet pipe 9 which extends through the wall 1 into the interior of the muffler body 1. The inlet pipe 9 is located at one side of the muffler body and is welded at 10 to the wall 1. As best seen in Figure 1 of the

drawing, the inlet pipe is formed with an obliquely cut inner end 11 which defines a deflector 12 having a sharp end portion 13 which is extended partially through the wall 6 of the body and is welded thereon, as shown at 14. It will now be understood that the inlet pipe will be firmly secured in the body 1 of the muffler. Near the inner end of the inlet pipe 9, a depression is formed defining a stop 15 for limiting inward movement of the free end of the exhaust pipe 8. As shown, the exhaust pipe is surrounded by the inlet pipe 9 and, in order to retain the device in operative position on the exhaust pipe, the inlet pipe is split at 16 and a clamp 17, of the split collar type, surrounds the split portion 16 of the inlet pipe. The clamp 17 has bolts 18 which are tightened about the inlet pipe for retaining the muffler in operative position on the exhaust pipe. Loosening of the bolts 18 may be effected, of course, for permitting removal of the muffler from the pipe.

In order to permit emission of exhaust gases from the interior of the muffler body 1, I provide an outlet pipe 19 which is relatively small with respect to the inlet pipe 9 and is disposed with its axis in the same horizontal plane with the axis of said inlet pipe 9. Both of the pipes 9 and 19 are located in the upper portion of the body so that an area 20 is provided throughout the lower half of the body for receiving circulating exhaust gases. The outlet pipe 19, as best seen in Figure 2, extends through the wall 6 of the body 1 and is secured therein by means of a weld 21. The inner end portion of the outlet pipe is oblique in formation, as shown at 22, to define a deflector 23 which terminates in a sharpened end portion 24. The end portion 24 extends partially through the wall 1 and is welded thereto, as shown at 25. A rigid mounting for the outlet pipe in the body is, therefore, provided. It should be understood that it is not absolutely necessary to provide a cut away portion for the outlet pipe, as the weld 21 will firmly mount said pipe in the body. The weld 25 and portion 24, however, impart greater rigidity to the structure. The outer end portion of the outlet pipe 23 is undercut obliquely at 26 so that the exhaust gases escaping through the outlet pipe will tend to be deflected downwardly.

As will be observed by referring to Figure 1 of the drawing, the inner end portion of the outlet pipe 19 extends past the plane of the outer end of the inlet pipe 9 so that effective distribution of gases within the muffler will be insured and direct flow of the gases from the inlet pipe to the outlet pipe prevented.

It is thought that the construction of my improved muffler will now be understood. It is desired to call attention to the fact that actual tests have shown my improved muffler to be far superior in operation to other mufflers heretofore placed in use. As heretofore stated, the use of my improved muffler improves the operation of an internal combustion engine for the reason that back pressure through the exhaust pipe and back into the exhaust manifold is largely eliminated. The results of the elimination of back pressure are greater efficiency from a given amount of fuel, also, carbon in the motor will be decreased, and the exhaust gases will be freed rapidly.

It is further desired to emphasize that the use of my improved muffler will be effective for eliminating the blocking of the muffler inlet pipe with motor waste. This will eliminate the trouble and expense of cleaning the muffler inlet pipe, a job for which a consistent charge is usually made when performed by automobile mechanics.

My improved muffler is simple in construction and cheap to manufacture. It is thought that further description is unnecessary.

Having thus described the invention, what I claim is:

1. In a muffler, a body, an inlet pipe carried by the body and having its inner end portion cut downwardly and rearwardly on an incline to define a deflector, the outer end of said inlet pipe being split, a clamp surrounding the split portion of the inlet pipe, said inlet pipe being adapted to surround an exhaust pipe and said clamp securing said inlet pipe in operative position on said exhaust pipe, a stop on the inlet pipe for limiting inward movement of the exhaust pipe,

means retaining the inlet pipe within the body, an outlet pipe carried by the body, and means securing the outlet pipe in operative position on the body, said body receiving exhaust gases from the exhaust pipe through the inlet pipe for circulation in said body and exhaust through the outlet pipe with a minimum of back pressure in the exhaust pipe. 5

2. In a muffler, a body having end walls, an inlet pipe extending into the body through one of said end walls and having a cut away inner end defining a deflector and a sharpened end portion for said deflector, said sharpened end portion extending through the opposite end wall of the body, means securing said sharpened portion in said end wall, said walls rigidly mounting the inlet pipe on the body, and an outlet pipe having its axis disposed in the same horizontal plane with the axis of the inlet pipe and extending through one of the walls of the body, 10 means securing the outlet pipe on said wall, said outlet pipe having a cut away inner end defining a sharpened end portion secured in the other wall of the body, said body receiving exhaust gases from the exhaust pipe in the inlet pipe and 15 circulating said gases within the body to flow to the atmosphere through the outlet pipe, said deflector for the inlet pipe deflecting the gases downwardly within the body and reducing back pressure of the exhaust gases within the exhaust 20 pipe. 25

3. In a muffler as claimed in claim 2, wherein the outlet pipe is relatively small with respect to the inlet pipe for slightly restricting the outflow of exhaust gases and assuring complete 30 muffling of motor noise. 35
